ABSTRACT OF THE DISCLOSURE

An apparatus is described for timing the duration of each of a succession of events which are represented by a binary code. The coded events and their respective durations are loaded upon command from a remote computer via a computer interface into the appropriate orders of a shift register which closes a recirculating storage loop including a delay line. The data organization in the storage loop also includes an elapsed time field which is incremented each $\frac{1}{60}$ of a second by a sidereal time control. The active event (marked by a marker bit in the field) is stored in an output function buffer while its timeout (scheduled duration) is stored in a state timeout buffer. At each $\frac{5}{60}$ of a second the elapsed time is compared with the state timeout and upon comparison the marker bit is moved to the next following field to load the next function into the output function buffer and the corresponding timeout into the state timeout buffer. Upon the next occurring $\frac{1}{60}$ second sidereal time pulse (thus completing a full second count) the output function buffer loads an output function register to control the output function, and the elapsed time field of the storage is reset to zero. Thus, no cumulative errors in timing occur. Since the recirculation rate is 111.5 microseconds, all data processing can proceed at a rate much faster than the $\frac{1}{60}$ second minimum time interval. The circulation of data and the signalling of the presence of the bits and fields in the shift register is vested in a clock pulse generator, a bit counter and a field counter. These control all loading, incrementing, comparison, etc., when the respective data is present in the correct orders of the shift register. Parity check and parity generation is provided. If a field is unused, its state timeout is zero and this causes the field to be skipped by advancing the marker bit to the next active field within the $\frac{1}{60}$ second.

This invention relates to operation sequence controllers and more particularly to an apparatus for controlling the duration and sequence of a succession of controlled events.

The electronic computer is playing an ever-increasing role in modern life. Because of its tremendous memory capacity, speed, and the ability to analyze complex inter-relationships, it is ideally suited for analyzing a set of conditions and recommending or taking remedial action to optimize the performance of the controlled environment. One such application is that of traffic control wherein the information with respect to vehicle flow and distribution in the controlled area is communicated to the computer by vehicle sensors located along the streets and highways. The computer then analyzes this traffic pattern in conjunction with data from traffic study histories and makes a decision as to the optimum schedule of vehicle control devices such as stoplights, and one-way street signs, to achieve the maximum vehicle flow. The computer's decision is then transmitted to the individual controllers to implement the computer's decision.

In an application such as that just described the changes in the traffic pattern (except for emergency conditions such as collisions, vehicle breakdowns, fire, or ambulance calls) are slow relative to the operation speed of the elec-

tronic computer. As a consequence the computer is seldom employed full time in traffic control. It is time-shared with other jobs. When the computer is "on-line" and processing the traffic flow problem, it is desideratum that it be able to communicate with and alter the scheduling of each remote traffic signal controller in the shortest practical time, and that the controller be able to effect any light sequence dictated by the computer.

While the instant invention is not concerned with either the use of a computer for calculating the optimum scheduling of the events or with communication between the computer and the controller which comprises the invention, the foregoing background information has been set forth as a sort of functional specification of the environment in which the invention is particularly adapted to operate. The background information also serves to equate the structure of the controller to the operation of a computer with which it must be compatible.

The programmed control of discrete events involves the identity and sequence of events and either time sequencing or event completion sequencing. In the timed event type of controller the duration of each event is preordained (at least for the period between schedule changes). Typical of this type is the ringing of classroom bells in a large school complex. Here, the schedule is relatively static and requires infrequent change. For this application a master controller employing a punched tape, plugs in a revolving drum, or other variable time-controlled circuit closing device is adequate for the purpose. Where schedule changes are more frequent faster and more readily changeable storage media may be employed. Examples of these include magnetic tapes and drums and other storage devices conventionally used to store data and programs in an electronic computer. While the program control of an electronic computer is somewhat analogous to the instant invention, in that it controls the sequence of operation of the various elements of the computer, it differs in one basic respect. A programmed electronic computer does not employ time as an independent variable in the program. Either each successive step in the program must be completed in the time allotted for the program step or the program computation is allowed to proceed at its pace to completion. The operational element then signals the completion to the program control which then steps to the next scheduled event or to some other event which might be dictated by the results of the previous computation. Thus, the computer program control does not, for example, schedule function A for two seconds, followed by function B for three seconds, etc.

Conventional prior art traffic controllers do control both the duration and sequencing of the traffic signals under their control. These controllers have also hitherto been connected to computers which dictate the light schedules. However, these prior art controllers suffered from incomplete flexibility, in that they had several preordained fixed programs upon which the computer could draw. If the particular stored programs did not fit the particular traffic conditions, then the program which best approximated the optimum program was perforce chosen as a compromise. This compromise program all too frequently aggravated an already congested traffic flow. The limitation on the variety of available programs in prior art controllers arose through the use of mechanical circuit closers such as cams and coacting electrical contacts, operated thereby. Necessarily structural complexity limited flexibility.

By borrowing from the digital techniques of the electronic computer art, the controller comprising the instant invention affords complete flexibility without duplication of components. In the preferred embodiment thereof it employs a recirculating delay line memory into which are

written coded instructions which identify the sequence of events and the duration of each of the events. As these instructions recirculate they are continuously examined to ascertain if the duration of the event in progress has expired. If so, the next scheduled event becomes active and its respective duration measured. Because the instructions are in coded form, and include both function identity and the associated duration, they may be written into memory in any sequence and for any respective duration within the limits of the apparatus, barring, of course, conflicting or impossible sequences, as for example, tapping a hole before it is drilled, if the controller were used as a machine tool controller.

In addition to the achievement of complete flexibility and compatibility with the operation of an electronic computer, the instant controller utilizes the recirculating memory for arithmetic and other logical functions so as to achieve a greater economy in the equipment. With the advent of micro-miniature solid state logical devices the controller can be fabricated economically in mass production and is well suited to the severe service conditions encountered in the average city street corner. Further, because of its utilization of digital techniques, it is capable of monitoring its own operation and signalling a malfunction. Thus, instead of dispatching a service man, the computer need only transmit a repeat of the program to correct the majority of malfunctions. If a breakdown occurs, which cannot be corrected by the computer, this breakdown is signalled and a standby energy initiated until a service man can correct the difficulty. In the case of a traffic intersection, this would call into action an emergency program with red and yellow blinker lights or some other suitable combination of lights.

In accordance with the foregoing, it is an object of this invention to provide an apparatus for controlling the operation of a plurality of work circuits in any order and for any time duration, wherein the schedule of operation is stored in a digital memory together with the duration of each of the scheduled events, and the passage of time is counted starting with the initiation of each new event and compared continuously with the scheduled duration of the event in progress until they are equal, when the next scheduled event is initiated.

A further object of the invention is to provide an apparatus in accordance with the foregoing object wherein the digital memory is a recirculating delay line which is also employed as a counter to count the elapsed time of each successive event.

Yet another object of the invention is to provide an apparatus for controlling the sequence and respective durations of a plurality of controllable work functions in which the sequence and durations of the respective controlled functions are stored as digital manifestations in a memory which is cyclically accessed at a rate in excess of the basic timing interval, the timing intervals being counted and compared against the scheduled duration of each successive event and upon equality the time count is reset and the next event control activated.

The foregoing and other objects, features and advantages of the invention will be apparent from the following more particular description of a preferred embodiment of the invention, as illustrated in the accompanying drawings.

In the drawings:

FIG. 1 is a schematic flow diagram illustrating the functional cooperation of the elements.

FIG. 17 is a circuit diagram of the circuits for controlling the loading of a new schedule of events.

FIG. 18 is a circuit diagram of the loading circuits.

FIG. 19 is a circuit diagram of the master reset control.

The organization of the data in memory is shown in FIG. 2. Basically, the data is arranged in ten fields (A through J) of twelve bits each. Fields A and B contain the elapsed time count, while Fields C through J contain the successive functions and their respective directions. This data circulates serially-by-bit, serially-by-field through the closed data circulation path, including a delay line and a shift register, in synchronism with the stepping of a bit counter and a field counter whose combined outputs identify the contents of the shift register at all bit and field times.

In FIG. 2, Field A (the first vertical column) contains in the first bit position thereof a binary zero or binary one mark (SP) which is inserted to render count of the binary one bits in Fields C through J (including the SP bit) odd. Bit positions BT2 and BP10 through BP12 are unused. Bit positions BP3 through BP9 (labelled SC-1, SC-2, SC-4 . . . SC-64) are allocated for storing the so-called "synch-count." These represent $\frac{1}{60}$ second of the elapsed time of the active function in progress, and are incremented by one count each $\frac{1}{60}$ second by a sidereal time control operated from the 60 cycle commercial power supply. These binary bits, as they circulate through the delay line closure act as a pure binary counter. When $\frac{59}{60}$ are accumulated in the synch-counter in Field A, a carry anticipation signal is generated. This signal, upon the next change in the synch-count, increments the binary count in bit positions BP3 through BP9 of Field B, these positions constituting the elapsed time counter (ETC), and also resets the synch-count to zero. Bit positions BP1 and BP2 in Field B are unused, as are bit positions BP10 and BP12. Bit positions BP11 of Field B stores the elapsed time parity bit ETP which renders the elapsed time bit count (Fields A and B except SP) always odd.

Fields C through J are identical in format, but differ in information content. These fields store the function to be performed and the duration of the function, as well as control bits that indicate which of the fields is active as a control. Specifically, bit position BP1 of Fields C through J store the SSLI (state storage loading indicator) bits, these bits being used for sequencing the loading of the memory from the computer interface. Bit positions BP2-BP4 store the state function assignment in a three bit binary code (eight combinations). The notation S2FA denotes the first function assignment, S2FA the second

function assignment, etc. The states proceed sequentially by field and denote the sequence of the functions. Bit position BP5 is used to denote which state is active. Thus, one only of the bits in BP5 (Fields C through J) will contain a binary one; all others will be zero. As each state's function control is completed, the SISR (state indicator shift register bit) is shifted one field position to the right (from C to D to E . . . to J to C). The measure of the duration of each sequential function in Fields C through J is stored as a binary coded number in bit positions BP6 through BP12, denoting the number of seconds of duration of each separate event. When the scheduled duration of any active function equals the elapsed time (ETC), the control shifts to the next following function.

From the foregoing explanation of the data organization within the recirculating memory, it will be apparent that with eight states (Fields C through J) available, eight successive events or functions can be scheduled. The function in each state can be chosen from eight different functions, there being three bit positions (BP2-BP4) for the function assignments. Thus, with eight states and eight different functions, 8^8 different sequences of schedules may be programmed. If one couples the possible time durations to the sequences, the number of different possible schedules becomes extremely large, particularly since the duration of any state may be scheduled from zero seconds to one hundred and twenty-seven seconds, there being seven bit positions available in the state time-out bit positions BP6-BP12 in Fields C through J. Should it be necessary or desirable to increase the available number of functions beyond the eight illustrated, the data capacity of the system need only be expanded by the requisite number of bits. So, also, if a greater number of states beyond the eight illustrated is required, the number of data fields can be expanded. This expansion obviously requires an expansion of the circuitry necessary to process the additional data, but it does not alter the basic operation of the invention.

Timing

Since in a delay line storage system the data bits circulate continuously in a closed loop, some time reference is necessary in order to establish the identity of the data bits which are present at some reference position in the loop. As will be explained with reference to the timing diagram description, the reference position in the loop has been chosen as the first cell of the shift register which is connected in series with the delay line. This is not only convenient but also logical, since all of the processing of the data occurs in the shift register.

The timing diagram in FIG. 3 represents the data content of the ten orders of the shift register at various bit times. The scale across the top of the drawing labelled CSC-1 to CSC-10 represents the respective cells or orders of the shift register. The vertical scale represents the various bit times BT1 to BT12 for all of the data Fields A through J. The notation "PF" denotes the previous field, and the numbers standing alone in the grid spaces represent the bit positions of the instant field which occupy the shift register cells at the various bit times. Thus, by way of example, if the instant of time were bit time five (BT5) of Field G (G5), then the first five bits of Field G will occupy the shift cells CSC-5, CSC-4, CSC-3, CSC-2 and CSC-1, respectively. The eighth through twelfth bits of the previous field (Field F) will occupy the shift cells CSC06 through CSC-10 in inverse order, respectively. At other bit times from BP1 through BT9 the shift register will contain various proportions of two successive fields. From BT10 through BT12 the shift register will contain the bits of a single field only. As will be apparent when the circuits are examined in detail, it is possible to make multiple uses of the same circuit elements by gating them into action at various bit and field times, so that they may operate upon the data then present in the various

cells of the shift register. This gating is under control of a bit counter and a field counter, which counters step synchronously with the shift of the data through the shift register. Thus, in the example chosen above, the bit counter will register a "5" and the field counter a "G" to produce the combined time of G5, which is the logical AND of BT5 and FTG (field time G).

In addition to the bit and field times, there are three other varieties of time that are of significance in the operation of the invention. The first of these is clock time. This is the basic coordinating means that synchronizes the operation of the circuit elements. It originates in a stable oscillator and frequency divider that yields five timing pulses TPA, TPB, TPC, TPD, and TPY per bit time. These timing pulses control the shift of data through the shift register, the processing of the data within the shift register, the entry of data into the delay line, and the timing of the data processing circuitry external to the data loop, in cooperating with the bit and field counter generated time references. Thus, an event is scheduled by field time, bit time, and by one of the clock times TPA through TPD.

The remaining time references, for convenience called "sidereal time," are sixtieths of a second and seconds. The sixtieths of seconds are referred to as "synch time" (SC in FIG. 2) and originate with the 60 cycle commercial power supply. The seconds (derived by counting sixtieths of synch time) are the elapsed time (ETC of FIG. 2). The means for generating these various times will be described in detail when the circuits are described.

System configuration

The overall system configuration is shown in block diagram form in FIG. 1. Because of the necessarily complicated interconnection of the major elements of the system and the multiple use of common elements, it has been necessary to take liberties with the drawing of FIG. 1. It, therefore, partakes more of the nature of a flow diagram rather than a circuit diagram, in that it illustrates only the gross flow of data and controls. Some of the elements shown in FIG. 1, while they are functional entities, are not necessarily susceptible to isolation in any one drawing of the actual circuit diagram. Various other simplifications have been exercised in FIG. 1 so as not to obscure the broad overall functional interplay of the elements.

The basic memory loop in FIG. 1 consists of the delay line 233 and a shift register connected to provide a continuous circulation of the data bits. Since delay line storage requires retiming and shaping of the data pulses, other elements, such as the level detector 232 and the driver 234, are necessarily provided. The level detector 232 detects the sense of the output response as a binary one or binary zero and produces the requisite input (or no input) to the first cell, GSC-1, of the shift register. The driver 234, timed by one of the pulses from the clock pulse generator 7 (as shown by line 7A) produces a pulse (or no pulse) having the required electrical and timing characteristics to excite the delay line 233 in timed synchronism with the flow of data into, through, and out of the shift register. A data pulse entered into the delay line 233 exits after a delay of approximately 111.5 microseconds for sampling under control of the clock pulse generator 7 and entry into the first shift cell CSC-1 of the shift register. The shift register consists of ten cells CSC-1 to CSC-10 which are broken into six groups as shown. For the simple shift of data, the shift cells are connected to the clock pulse generator 7 (via line 7A) for synchronized shifting in time with the exit of data from, and entry of data into the delay line 233. With ten shift cells and a data base of one hundred twenty bits (ten fields of twelve bits each), the delay line has a capacity of one hundred ten bits.

Since all processing of data occurs in the shift register, it must be capable of producing parallel outputs from

its shift cells, yielding to parallel inputs into its shift cells, and in certain instances altering the nature of the data as it shifts between cells. For the last-named function, circuits are intervened between the appropriate orders of the shift register, which circuits are normally operative to pass on the data without alteration and at special times in the cycle (under control of the bit and field counters) are operative to alter the data as it shifts. One of these data-altering circuits is the incrementer 5 which intervenes between the first and second shift cells CSC-1 and CSC-2. This incrementer is normally operative to pass the data without alteration. However, when the sidereal time control 11 detects either a $\frac{1}{60}$ second or a one second time change, it causes the incrementer 5 to add one to the synch count, or to the elapsed time count, in Fields A and B, respectively.

The fifth storage cell CSC-5 is shown isolated from the adjacent cells because all data bits (except parity bits) which are to be singularly inserted into the data stream are inserted into this cell. The ninth cell CSC-9 is similarly isolated because all singular bit resets (except parity, are performed in this shift cell. The use of these two shift cells for these functions results in the economy of circuitry.

The parity generator 6 counts the oddness or evenness of the data bits for each of the respective data fields for which parity is to be generated, and passes a zero or one to the driver 234 in bit positions BP1 of Field A (SP) and in BP11 of Field B (ETP) to render the bit count odd. Thus, all data entering the delay line 233 has appropriate parity bits added thereto (or not added) to render the bit count odd. The data coming out of CSC-1 is similarly checked for parity. If this parity fails to check, the system is converted to a neutral standby condition and an alarm alerted. Parity is generated only when the synch time or elapsed time is incremented, or when a new program is inserted into memory. These functional interrelationships are shown in FIG. 1 by the line 10A which transmits a parity check error signal from the parity checker 10 to the output function register 15, to set it to a neutral function. In the case of a traffic controller this neutral function would be flashing red and yellow lights at the respective secondary and primary streets at an intersection. The activation of the parity generator 6 is shown by the connection 11A from the sidereal time control circuits 11 and by the connection 12A from the load control circuits to the parity generator.

The cycle time for the 120 bit data capacity is 120 microseconds. Thus, any necessary processing of the data can proceed at this rate. Since the minimum time for any scheduled event is one second, there is more than adequate time to complete all processing before the next event becomes operative. This includes loading a new program. The regular incrementation of the synch count and elapsed time count within Fields A and B is accomplished upon the next circulation of the data after the transition of the sixty cycle line. Since over 138 cycles of the data occur during each of the periods of the 60 cycle line (16.7 microseconds), the incrementing of these fields will occur substantially concurrently with the transition of the sixty cycle line. As will be explained in detail, provision is made to prevent accumulations of timing errors by initiating the sequencing of events with the sixty cycle timing, even though the coordination of the elements is achieved by the master clock pulse generator. Thus, the asynchronism of the sixty cycle power supply and the master clock pulse generator is compensated by, in effect, running the elapsed time count continuously, anticipating the need to change the event at the timeout duration minus $\frac{1}{60}$ second, and effecting the change upon the next transition of the sixty cycle timing wave.

For a point of departure for understanding the opera-

tion of the apparatus it will be assumed that a new program has just been loaded into memory and that the first state (and function) is operative. In this condition the synch count (Field A, BP3 to BP9) is less than 59, and the elapsed time count (ETC) in Field B (BP3-BP9) is reset to one second. The first state function assignments (SIFA) bits in BP2 to BP4 of Field C are loaded in the output function buffer 14 and in the output function register 15 to control the requisite work functions. The state timeout duration in BP6 to BP12 of Field C is stored in the state timeout buffer 16. The state indicator storage register bit in BP5 of Field C is a binary one, while the comparable bits in Fields D through J are binary zeros. This marks Field C as containing the active state.

As the sidereal time control 11 produces a $\frac{1}{60}$ second timing pulse, the synch time will be incremented by the incrementor 5 as it shifts between CSC-1 and CSC-2 of the shift register. When the synch time equals sixty, the elapsed time counter in Field B will be incremented to count seconds. When the elapsed time equals the state timeout stored in buffer 16, comparator 17 produces an output on line 17A. This activates the active state control 18 to shift the active state bit (BP5) from Field C to Field D. It also controls the reset of the synch count to zero and elapsed time count to one as well as the loading of the new state function assignment (from Field D) into the output function buffer and into the output function register. It also causes the parity generator 6 to produce a new parity. Field D then becomes active to control the output function under control of the state timeout loaded into the state timeout buffer from Field D. The sequencing for each separate state continues to Field J and back to Field C, each state persisting for the number of seconds stored in the respective field bit positions BP6-BP12. This cycling of the controls continues until the computer signals that a new program is to be loaded.

If less than the total capacity of the storage is required for the schedule (less than eight sequences of events), the state timeout for the unused fields will be stored as zero seconds. This (by circuits to be described) will cause those states to be skipped. Since the minimum duration is one second for any event, the output function register will retain the previous function assignment until a new function assignment having at least one second duration is found. If the schedule requires a function duration in excess of 127 seconds, then two adjacent states may be loaded with the same function, each with a proportionate share of the total event timeout.

When the computer signals a new program is ready, the controller is allowed to complete a program through Field J when it sends a cycle complete signal to the load control 12. This load control then controls the loading of each new field data as it passes through the shift register under control of the state storage loading indicator bits in BP1 of Fields C through J. The cycle complete signal actually occurs approximately $\frac{1}{60}$ of a second before the controller would normally shift state to state 1, and enter the new state function assignment into the output function register. The cycle complete signal and the load signal from the computer permit the first state function assignment and timeout from the first field of the old program to enter the output function buffer and state timeout buffer respectively, but set up conditions to prevent further state shifting until loading is complete. The computer interface then loads at least the first field (Field C) of data within the $\frac{1}{60}$ second before the contents of the output function buffer is transferred to the output function register. The new and now loaded, data from Field C (state 1) enters the state timeout buffer and the output function buffer upon the next recirculation of this data through the shift register. When at the end of $\frac{1}{60}$ second the state timeout occurs the new data will be available in the output function buffer for entry into the output function register for uninterrupted control. Meanwhile, loading of the data into Fields D through J will continue

immediately following the loading of Field C or at least as fast as the interface and the controller can cross-communicate with one another. Since the new state 1 data was certainly loaded within $\frac{1}{60}$ of a second, because the interface 13 would not have signalled its readiness unless it was at least loaded with the data for that state, the new state 1 data will have a minimum duration of one second. This then allows the remaining data to be loaded in one second, which is more than adequate for this operation. When loading is complete, and it will be complete within one second, except for malfunction, the state shifting is permitted to resume. Necessarily, this requires that State 1 always have a state timeout other than zero. This is achieved simply through computer programming. Each of the circuits for effecting the functions described broadly hereinabove will now be examined in greater detail. Before proceeding, however, it is necessary to digress briefly and set forth a new drawing notations that have been adapted.

Drawing conventions

In FIGS. 4 through 18 various drawing conventions have been adopted which simplify the understanding of the operation and the interconnection of the various circuit elements. These conventions permit a technician to select and interconnect the requisite standard solid state digital logical elements into the complete apparatus. The circuit elements employed include triggers and latches and various logical elements such as an AND gate, OR gate, NOT, and a simple gate. Arrows at a circuit crossing indicate the direction of the control potential (or current flow), and that the wires are connected at the intersection. A black half arrowhead entering a circuit element indicates that the circuit element will operate responsive to a relatively positive DC input. Conversely, a white half arrowhead indicates the circuit operates responsive to a relatively negative DC input. When the circuit is operative (performs its labelled function), it produces an output response which is positive if the output line has a black half arrowhead, or negative if it has a white half arrowhead. A full arrowhead (black or white) indicates that the device operates in response to a pulse, as opposed to a DC input. A trigger or a latch will have a black half arrowhead on the exit line from the binary one side of the bistable device and a white half arrowhead on the binary zero exit line. This denotes a positive output on the "one" line when the device is set (binary one). The zero line will be positive when the device is reset.

Clock pulse generator

The clock pulse generator is shown in FIG. 4 and the relative timing of the pulse outputs therefrom are shown in FIG. 4A. The basic timing originates in the 2 megacycle oscillator 31 which produces the square wave output shown in the first waveform of FIG. 4A. The square waveform varies between the reference level (which may be ground) and a relatively negative potential, as indicated by the white half arrowhead on the output line 31A of the oscillator. The output pulses from oscillator 31 are fed directly to the gates 32 and 33 and inverted (in inverter 38) from which they are fed in parallel to the gates 35 and 36. The gates 32, 33, 35 and 36 all operate responsive to a negative-going pulse (manifested by the white full arrowheads) from the oscillator and a negative DC conditioning level (manifested by the white half arrowheads) fed from the outputs of the trigger 34 to the gated inputs of trigger 37 and from the outputs of the trigger 34 to the gated inputs of the trigger 37. These triggers produce a constant positive DC output for the respective binary states, and switch state in response to a negative-going change in the input potential. In effect, therefore, the trigger inputs are capacitively coupled so that they switch in response to a change in the input potential of the requisite direction.

The TPX and TPY triggers 34 and 37 are cross cou-

pled to produce a Gray code, that is to say, only one trigger at a time switches state. Laboring the analysis further, so as to illustrate the drawing conventions employed, let it be assumed as a point of departure that the TPX trigger 34 is in the binary zero state and the TPY trigger 37 is in the binary one state. In this state, line 34-0 is positive, line 34-1 negative, line 37-0 negative, and line 37-1 positive. With line 37-0 negative, gate 32 is primed (white half arrowhead input). With line 34-1 negative, gate 35 is similarly primed. Gates 33 and 36 are not primed because of positive potentials from line 37-1 and 34-0. This is the condition shown in FIG. 4A just to the right of the beginning of the timing chart. When the oscillator 31 produces the first negative-going excursion, the primed gate 32 will respond (shown by white full arrow) to yield a negative output to switch trigger 34 to the one state. The primed trigger 35 yields no output because the negative-going pulse from oscillator 31 is inverted in inverter 38 to yield a positive-going pulse to which the gate 35 is insensitive. Furthermore, trigger 37 is already in the binary one state. The first transition results in both triggers in the binary one state.

With both TPX and TPY triggers in the binary one state, the next occurring positive-going excursion of the output from oscillator 31 will affect neither the gate 32 nor the gate 33. The inversion through NOT gate 38 will pulse gates 35 and 26. However, only gate 36 will be primed by a negative output from trigger 34 (now in the one state). Thus, the inverted positive-going pulse from the oscillator will switch trigger 37 to the binary zero state, leaving trigger 34 in the one state.

When the next negative excursion of oscillator 31 occurs, gates 32 and 33 will receive the requisite pulse polarity. Gates 35 and 36 will receive positive-going pulses and will not respond. Of the gates 32 and 33, only gate 33 will be primed by the negative condition of line 37-1 (trigger 37 in zero state). Thus, trigger 34 will switch to the zero state leaving trigger 37 in the binary zero state.

Upon the next positive excursion of the timing waveform, trigger 37 will switch from the zero state to the one state. This results from the inversion in NOT gate 38 and the priming of gate 35 by the negative potential from trigger 34 (in the zero state). Gates 32 and 33 will not respond to the positive transition of the waveform. Trigger 34 remains in the zero state while trigger 37 switches to the one state. This restores the triggers to the initial state from which the explanation proceeded. From the foregoing it will be apparent that trigger 34 switches on negative excursions of the timing waveform, while trigger 37 switches on positive excursions of the waveform. This results in the frequency division of the basic waveform frequency of 2 megacycles in two 1 megacycle waveforms (TPX and TPY) having a phase displacement of one quarter wavelength. This one quarter wavelength phase displacement is further exploited to produce four timing pulses per bit period by logically ANDing the outputs from the triggers 34 and 37.

In the initial state (TPX=0, TPY=1), lines 34-0 and 37-1 are both positive. These polarity states, when combined in AND 39 (both inputs with black half-arrowheads), produce a negative output response (white half-arrowhead). This output response, when inverted in NOT 40, produces the positive TPA pulse on line 40A, which pulse is shown in the timing diagram of FIG. 4A. The non-inverted TPA pulse appears on lines 39A.

Similarly, the TPB pulses appearing on lines 42B and 41B are achieved by combining the positive outputs of lines 37-1 and 34-1 in AND 41 and inverting in NOT 42. The TPC pulses on lines 44C and 43C are achieved by combining lines 37-0 and 34-1 in AND 43 and inverting in NOT 44. The TPD pulses on lines 46D and 45D result from combining lines 37-0 and 34-0 in AND 45 and inverting in NOT 46. Thus, for every bit period of one microsecond length, there will occur one TPX and one TPY pulse of $\frac{1}{2}$ microsecond in length,

and one each of the TPA, TPB, TPC, and TPD pulses each of a $\frac{1}{4}$ microsecond in length having the relative timing shown in FIG. 4A.

The TPY pulse is used only to time the pulsing of the delay line 233 in FIG. 13. The arrow at the end of the line 37-0 and the figure number in parentheses denotes that the TPY pulse is used in FIG. 13. Incoming and outgoing lines on other figures will denote the source or destination of the connection. The TPA through TPD pulses are used in all figures and, therefore, their destinations are not labelled. Wherever in another figure the legend TPA, TPB, TPC, or TPD appears, it will be assumed that these are timing pulses originating in FIG. 4.

Bit counter

As was stated in the explanation of the flow diagram of FIG. 1 the bit counter 8 and field counter 9 keep track of the bits as they shift through the shift register. The bit counter 8 is shown in detail in FIGS. 5A and 5B. Basically, it consists of four triggers 75, 78, 81, and 84 interconnected as a pure binary counter with a reset so that the count does not exceed twelve (there being twelve bits per field). The counter increments upon the negative TPA pulse on line 39A (from FIG. 4). This pulse activates either gates 73 or 74 to complement trigger 75, because of the priming coupling from the output lines 75-0 and 75-1 thereof. Thus, if trigger 75 is in the zero state, line 75-1 is negative to prime gate 73 which responds to the negative TPA pulse (full white arrowhead) to switch trigger 75 to the one state. Upon the next negative TPA pulse and the switching of trigger 75 from the one to the zero state, the negative transition of line 75-1 coupled with the negative potential on line 78-1 (trigger 78 is in the binary 0 state) will switch trigger 78 to a binary one state. The next transition of trigger 75 to the one state produces a positive excursion of line 75-1 which has no effect upon gates 76 or 77. The next switching of trigger 75 from one to zero switches trigger 78 to zero. When it switches to zero, it complements trigger 81 through gate 79. By extrapolation, trigger 78 will complement trigger 81 through gates 79 and 80 upon each transition of trigger 78 from a one to a zero state. Similarly trigger 84 will be complemented through gates 82 and 83 upon every one to zero transition of trigger 81. This partakes of the natural binary progression where each bit (except the lowest) changes on every other change of the preceding bit in the progression. However, if this stepping were allowed to proceed unchecked, the counter would count up to fifteen (1111) which exceeds the field capacity. Therefore, when the bit count equals twelve (triggers 84, 78, and 75 in the binary one state), AND gate 72 will be activated in turn to operate OR 70 which produces a negative output to NOT 69 whose inverted output, when combined in AND 87 with the positive TPC pulse, sets the bit counter reset latch 86 which was reset by the immediately preceding TPB pulse. This latch, set at BT12, stays set into the next bit period (BT1) when its output is combined in AND gate 85 to reset the bit counter to all zeros through a negative control on line 85A to the resets of triggers 75, 78, 81 and 84. Since this condition represents a bit count of one, the twelfth bit time actually equals $8+2+1$. At the same time, that the bit counter is reset by the bit counter reset latch 86, the field counter (FIG. 6) is incremented by one count. The AND gate 71 with inputs from BC4 and BC8 (corresponding to BP13) insures the reset of the bit counter. When latch 86 is set at BT12 and TPC and its output used at TPA in the next cycle (BT1), it will reset at TPB time by BT1.

The bit times BT1 through BT12 are derived by logically ANDing the binary zero and binary one outputs from triggers 75, 78, 81 and 84, as shown by the legends appended to the AND gates 47, 49, 51, 53, 55, 57, 59, 61, 63, 65, 67, 71, and 72 in FIGS. 5A and 5B. The double arrowed notations on the input connections denote

the output line to which the AND inputs are connected and the polarity necessary to operate the gate. The AND gate 47 which produces the one bit time control BT1, operates responsive to four positive inputs and is connected to the zero output lines of the four triggers. Therefore, when these lines are all positive (0000) AND 47 operates to produce a negative output response which appears directly on line 47A and inverted (through NOT 48) on line 48A. Other combinations are similarly wired into the AND gates as labelled in FIGS. 5A and 5B. The appropriate outputs are inverted in the evenly-numbered NOT gates from 48 through 68 and in NOT 69 to produce positive and negative outputs for timing uses in the other figures, which uses are too numerous to label on FIGS. 5A and 5B.

Field counter

The field counter, FIGS. 6A and 6B, is substantially identical to the bit counter of FIGS. 5A and 5B with a few exceptions. The first exception is in the incrementing signal. Whereas the bit counter was incremented on every TPA pulse, the field counter is incremented whenever the bit counter resets. The field counter incrementing signal on line 85-1 occurs when the bit counter resets at TPA time of BT1, and operates through either gate 111 or 112 to complement trigger 113. Coupling of trigger 113 through gates 114 and 115 to trigger 116, the further coupling of trigger 116 through gates 117 and 118 to trigger 119, and the final coupling of trigger 119 through gates 120 and 121 to trigger 122 completes the binary frequency division in the same manner as in the bit counter. Because there are only ten fields (A through J), the field counter must reset following the tenth count (actually $8+1$). To this end the one outputs 122-1 and 113-1 are combined in AND 108 to energize OR 107 and NOT 106 to set the field counter reset latch 124 through AND 125 at TPC time if the bit counter reset latch 86 (FIG. 5) had been set at BT12, TPC time. The output from the field counter reset latch 124 resets the field counter triggers 113, 116, 119 and 122 at TPA time through AND 123. Thus, the field counter is incremented with every reset of the bit counter after twelve counts and is reset concurrently with the bit counter after ten counts. These two counters run continuously. In addition to keeping track of the data circulation through the shift register, they also control the entry of new data thereinto. Additionally, in coordination with the clock pulses they control the alteration of the data as it circulates.

In FIG. 6B the same safeguards for resetting the field counter to zero are provided as in FIG. 5B for the bit counter. AND gates 109 and 110, having respective paired inputs from the one side of triggers 122 and 116, and 122 and 119, force the reset for any count in excess of ten. These AND gates connect to OR 107 and NOT 106 to effect the reset previously explained. To obtain the field location signals, the zero and one outputs from the binary triggers constituting the field counter are combined in the even numbered AND gates from 88 through 104 and in AND 108 to provide the requisite negative and positive outputs directly and invertedly through the odd numbered NOT gates 89-105 and NOT 106. These field timing signals FTA through FTJ are used throughout the subsequent figures and are labelled therein with the appropriate legend to denote the connection to one of the lines of FIGS. 6A and 6B.

Sidereal time generator

The sixtieth seconds generator, referred to as the sidereal time generator merely to distinguish its time from the other system time bases, is shown in FIG. 8. It takes its timing from the sixty cycle commercial power supply which is filtered of high frequency transients and noise by the bandpass filter 154. The filtered 60 cycle sine wave is squared and the negative-going (or positive-going)

axis crossing of the square waveform detected in the zero crossing detector 155. The negative pulse output from the zero crossing detector sets the synch time latch 157 whenever the crossing occurs, actually sixty times per second. Since the data circulation is asynchronous, provision must be made to store the event and utilize it only once. Therefore, a synch interlock latch 160 is provided which resets the synch time latch when the count in the synch time field of the circulating data is actually incremented. Since the synch counter incrementation is inextricably bound to the operation of the sidereal time generator, certain operations thereof will be assumed and explained later so as not to complicate the explanation of FIG. 8.

With latch 157 set (in the one state) by the zero crossing detector and the synch interlock latch reset (zero state), lines 157-1 and 160-0 are both positive. This potential condition causes the synch count in Field A of the data to be incremented by one count at the next A3 time (Field A, bit time 3) and TPC. This incrementing produces a signal on line 143-1 (from FIG. 7 to FIG. 8) to coact with TPD pulse in AND 158 to set the synch interlock latch 160. With the synch time latch 157 and the synch interlock latch 160 both set, no further incrementing of the synch time can occur. With latch 160 set (at TPD time) the next TPA pulse and the absence of zero crossing detection (positive output from 155), AND gate 156 will be activated to reset the synch time latch 157. Immediately thereafter at TPB time, AND 159 will respond to reset latch 160. Since a complete data circulation occurs in 120 microseconds, this sequential setting of latch 157, setting of latch 160, resetting of latch 157 and resetting of latch 160 will occur long before the next 16.67 milliseconds time period intervenes to produce the next synch pulse. If the zero crossing detector produces an output when the synch time data has just passed the appropriate shift register position, the data will be around again within 120 microseconds. If the zero crossing occurs when the synch time is just approaching the appropriate orders of the shift registers, or is disposed therein, the incrementing will occur substantially immediately.

The outputs from the sidereal time generator exit to the synch counter incrementing circuits of FIG. 7 and to the gating circuits to load the output function register of FIG. 16. The utilization of these controls will be explained when these figures are explored.

Incrementing the synch count

As is shown in the flow diagram of FIG. 1 the incrementing of the synch count in Field A and the incrementing of the elapsed time count in Field B is achieved by intervening an incrementing circuit between the first and second cells CSC-1 and CSC-2 of the closure shift register. This circuit and the first and second closure shift cells CSC-1 and CSC-2 are shown in FIG. 7.

As previously stated, the incrementing circuits only operate when the synch count or elapsed time count is to be incremented and then only when these specific data bits are being shifted through the shift register. Normally, therefore, these circuits operate to shift the data without alteration. In FIG. 7 a positive pulse on line 232A from the level detector 232 in FIG. 13 denotes a binary one, the absence thereof a binary zero. This pulse occurs (or does not occur) substantially coincidentally with the TPA pulse which through AND gate 126 corrects any minor inaccuracies in the timing of the delay line output. AND 126 sets latch 127 if the input is a binary one, or leaves it in the zero state (reset at TPD of the previous bit period). In either case latch 127 stores each successive bit at TPA time of each bit time. At TPC time the absence of a master reset signal on line 354-0 (a normal condition) transfers (through AND 129) a binary one to the first shift cell delay latch 130, or leaves the latch reset if the bit were a binary zero, the latch having been reset at TPB time in the same bit period. Latch 127, following the transfer, resets at TPD time.

Assuming first that no incrementing is required and that latch 130 stores each successive bit at TPC time of each bit period, then at TPA time of each respective bit period as a new datum bit shifts into latch 127, the preceding bit will shift out of latch 130 to trigger 139 constituting the second shift cell CSC-2. This simple shift is effected by coupling the zero and one output lines 130-0 and 130-1 through AND gates 133 and 132 to gates 138 and 137 respectively. The AND gates 132 and 133 are active to pass along the state of latch 130 because the increment counter latch 143 is reset to potentialize line 143-0 positively. Thus, at TPA time when the sample pulse driver 128 reproduces the TPA pulse, gate 137 or 138 will pass the state of latch 130 to trigger 139. Trigger 139 will condition gates in the next stage (CSC-3) similar to gates 137 and 138 so as to permit the trigger 139 to shift its datum bit during the same timing pulse period (TPA) that it is receiving a new bit.

If incrementing of the synch count is to be effected, the synch time latch 157 is set, as previously described, to render line 157-1 positive and line 160-0 positive. These potential statuses when ANDed in AND 140 with BT3 (bit time 3, FIG. 5) and FTA (Field Time A, FIG. 6) and a TPC pulse sets the increment counter latch 143. By reference to FIGS. 2 and 3, it will be seen that at BT3 the third bit of the instant field occupies CSC-1. If, as here, BT3 is ANDed with FTA, the instant occupant of CSC-1 is the third bit of Field A. FIG. 1 shows this to be the SC-1 bit, the low order bit of the synch count. Thus, if incrementing to be performed, the increment counter latch 143 is set at TPC time of that bit period when the 2⁰ bit of the synch time is stored in delay latch 130.

If one examines the rules for incrementing a binary series, he will see that the lowest bit of the series is invariably complemented, and that all bits higher than the lowest order bit are complemented so long as the preceding bits are all ones. This simple relationship is exploited to provide a serial alteration in the synch count bits as they shift from CSC-1 to CSC-2 (latch 130 to trigger 139). When latch 143 (increment counter latch) sets at TPC time with the first synch count bit in latch 130, it prepares AND gates 131 and 134 and deactivates AND gates 132 and 133. This provides an inverted, or crossed coupling, between latch 130 and trigger 139. Thus, when the first synch bit shifts from latch 130 to trigger 139 at TPA time (with latch 143 set), it will be complemented, or inverted, as it enters CSC-2. Thus, an exiting zero will enter as a one and vice-versa. This inversion of each succeeding bit, as it shifts, will continue until a one is entered into latch 139, which entry signifies (because of the inversion) that the zero had occurred in the series of bits before alteration. With trigger 139 thus set to the one state line, 139-0 becomes negative. This negative potential, when applied to OR 144, produces a positive output to AND 142 at TPA time of the bit period wherein the first significant zero shifts into CSC-2 as a binary one (because of complementing). At TPB time of the same bit period, AND gate 142 is fully activated to reset the increment counter latch 143 to interrupt the complementing of the synch count bits. Lacking a reset of the increment counter latch from the data itself, the latch is invariably reset at BT10 time through OR 144. At this time, the tenth bit of field B will stand in CSC-1. By reference to FIG. 1, it will be seen that both the elapsed time and the synch count will have passed the counter incrementing position. This insures that no alteration will be performed on any data contained in Fields C through J by the incrementing circuits. This safety feature protects the integrity of the program data.

Incrementing elapsed time count and resetting synch count

The incrementing of the elapsed time count BP3 to 75 BP9 of Field B is effected in a manner similar to that

employed for incrementing the synch count, once the decision is made that the elapsed time count requires incrementing. Basically, this occurs when the synch counter has accumulated one second of sixtieth seconds from the sixty cycle power supply.

Referring to FIG. 3, it will be seen that at BT10 of Field A, bit positions BP3 through BP9 of Field A will occupy CSC-2 through CSC-8 in respective inverse order. If these seven bits are examined in parallel at this time, the magnitude of the synch count can be determined. Each of the shift cell triggers CSC-2 through CSC-8 has an output line from both the zero and one sides of the trigger. The zero line is denoted by a white half arrowhead and the one line by a black half arrowhead. These output lines are logically combined in AND 145 (FIG. 9), as shown. Specifically, the one outputs from CSC-8, CSC-7, CSC-5, CSC-4 and CSC-3 are ANDed with the zero outputs from CSC-6 and CSC-2. When these are converted to the decimal equivalents they yield (in Boolean algebra) $1+2+4+8+16+32+\overline{64}=59$. Thus, when the synch count equals 59 (or in fact any succession of bits in these bit positions equals 59), AND 145 produces a negative response which is inverted in NOT 146 to a positive response. This, coupled with an A10 control (FTA and BT10) and a TPB timing pulse (in AND 147), sets the SC=59 latch 149 (synch count=59). This setting of latch 149 and the reset condition of latch 152 establishes the conditions precedent for examining whether the stored state timeout equals the elapsed time (FIG. 14), to be explored later. With line 149-1 rendered positive by the setting of the latch 149 at A10 time, latch 152 will set at C1 and TPC time from the output of AND 150, having as inputs thereto line 149-1, an FTC pulse, and a TPC pulse. Thus, at TPB time of B10 (between A10 and C1) the state timeout can be sampled.

The SC=59 latch 149 remains set until the next occurring $\frac{1}{60}$ second pulse initiates an increment synch count at A3 and TPC of a subsequent cycle, which incrementing is complete by A9 time of the same cycle. Actually, this produces a decimal equivalent value in the synch counter of 60. However, when at A10 time, this count enters AND 145 (FIG. 9), it produces a positive output (AND not satisfied) on line 145A which together with a TPB pulse, a BT10 pulse, and an FTA pulse operates AND 148 to reset the SC=59 latch 149. With 149-0 positive, and 152-1 positive (152 is still set), AND 153 is activated to produce a negative reset synch counter signal on line 153-1 (FIGS. 9 and 11). In FIG. 11, the reset signal on line 153-1 operates NOT 190 which at A10 time (FTA and BT10) combines in AND 187 with a TPC pulse to apply a synch counter reset pulse to line 186A. This line connects to the reset side of the trigger 139 (CSC-2, FIG. 7); triggers 178, 181 and 184 (CSC-3 to CSC-5, FIG. 11), and to triggers 194, 197 and 200 (CSC-6 to CSC-8, FIG. 12). It will be noted that bits BP3-BP9 of Field A occupy CSC-2 to CSC-8 at A10 time. Thus, the synch counter is incremented from 59 to 60, but is reset within one bit period to zero.

The zero state of latch 149 and the one state of latch 152 (FIG. 9) are further ANDed in AND 141 (FIG. 7) with B3 (FTB and BT3) and a TPC pulse to set the increment counter latch 143 to ready the inversion circuits between CSC-1 and CSC-2 to increment the elapsed time count beginning at TPA time of B4 when the first ETC bit shifts from CSC-1 to CSC-2 and ending with the detection of the first significant zero which resets latch 143, in the same manner as the synch count was incremented. The resetting of the SC=59 delay latch 152 at C1 time removes the conditions precedent to incrementing the ETC count, to resetting the synch count, and to examining the state timeout comparison with the elapsed time count.

If, however, when the state timeout was compared with the elapsed time count they were equal, then a new function assignment must be chosen and the elapsed time

must be reset to one second to start timing the new event. Without now exploring fully the state timeout comparison, it will be assumed that if the comparison were effected, it would have been achieved at TPB time of B10 when the ETC count was present in CSC-2 to CSC-8. This sets a latch 236 (FIG. 14) which renders the one output line 236-1 thereof positive (FIG. 11) for the duration of the set condition of latch 236. At B11 time (FTB and BT11) and TPC, AND 188 yields an output to OR186 which applies a reset pulse to line 186A to reset the triggers of cells CSC-2 to CSC-8 to zero. The line 236-1 (FIG. 14) also feeds AND 201 (FIG. 12) which also receives a TPC pulse and a B11 pulse (FTB and BT11) to set CSC-9 (trigger 204) to the one state. It will be noted that at B11 time, when the ETC count is reset to 0000001, the elapsed time occupies stages CSC-3 to CSC-9. The cell CSC-2, which is incidently reset at this time, contains BP10 of Field B, which, by reference to FIG. 2, is unused and a zero. The reset, therefore, has no effect upon this cell. This expedient permits the same reset circuits to be employed for both the synch count and the elapsed time count.

Should it have been noticed in following this rather complicated explanation, that the comparison of the elapsed time count with the state timeout storage occurred before the elapsed time count was incremented, the reset of the elapsed time count to one rather than zero provides the explanation. This permits the comparison to be initiated when the synch count equals 59 (before the ETC is incremented), so that the change in the function assignment can be predicted and synchronized with the sidereal time when the synch count goes to sixty (zero reset as hereinbefore explained). The detailed structure for providing this synchronization with the sidereal time will be explored more fully in the description of subsequent figures.

Parity check and parity generation

Whenever the synch count or the elapsed time count is incremented or reset, the configuration of the bits in Fields A or B changes. Therefore, upon each such change new parity must be generated to insure that the bit count (the number of ones in the examined series) is odd. If the count is even, a parity bit is inserted to render the count odd. As was stated in the section devoted to the organization of the data in memory, there are two parity bit positions, BP11 of Field B (elapsed time parity) and BP1 of Field A (state parity). The former of these (ETP) following as it does the elapsed time field checks the parity of the bits in Fields A and B. The latter of these checks the bits in Fields C through J. Since the number of one bits in Fields C through J changes only when a new program is loaded, parity for these fields needs to be generated only upon a change in program. The parity in all instances is checked upon every circulation of the data and checks principally the integrity of the delay line storage. It will, however, detect mis-operations of the shift register in certain instances.

Turning first to the parity checking, which is performed upon the output of the CSC-1, latch 127 (FIG. 7) by the circuits of FIG. 10. The output line 127-1 from the first shift cell trigger 127 is positively potentialized for a binary one at TPA time of each bit period in which a binary one occurs. This line is tested at TPB time of each bit period and used to complement the parity check trigger 165 (FIG. 10). This trigger (165) is first reset to zero during the bit period preceding the first bit of a field whose parity is to be checked. Specifically, the parity check trigger 165 is reset at A2 and B12, both unused bit positions. The first of these resets is effected by combining FTA, BT2, and TPC in AND 166 to active OR168 to reset trigger 165 to zero. The other reset is affected by combining FTB, BT12, TPC, and a lead from the zero output 241-0 of the normally reset cycle complete latch 241 (FIG. 14) in AND 167 to activate OR168

and effect the alternate reset of trigger 165. Thus, trigger 165 is reset to zero at A2 just before the checking of Fields A and B to obtain the ETP (elapsed time parity) and at B12 just before the checking of Fields C through J to obtain the SP (state parity).

With trigger 165 reset, all binary ones after BP2 in Fields A and B will complement trigger 165 once for each binary one. This results from sampling the line 127-1 at TPB time in AND 162 which feeds gates 163 and 164. Gate 163 requires negative inputs and is connected to the one output line 165-1 which is positive when trigger 165 is set. Gate 164 feeds from the zero side of the trigger by line 165-0. Thus, gates 163 and 164 are alternately active to direct the sampling from AND 162 to the zero and one inputs of trigger 165 in alternate succession. This successive complementing of trigger 165 continues from A2 through B11 (the parity bit). If the total number of bits (including the parity bit) is odd, the trigger 165 will reside in the binary one state by the end of TPB time of B11. If it does not so reside, it will indicate a parity check error by a positive potential on line 165-0. This condition is checked by combining line 165-0 with FTB, BT11, and TPC in AND 171 to set the elapsed time parity error latch 172. This latch remains set until reset by a master reset impulse or by a manual reset from switch 175.

The checking of the state storage fields C through J proceeds in a similar manner. Trigger 165, having completed its check of the elapsed time parity and delivered its results by TPC time of B11 is reset at B12 time, as explained. The ones from Fields C through J operating through AND 162 and gates 163 and 164 successively complement trigger 165 as does the SP bit in BP1 of Field A at each TPB time. At TPC time of A1 the condition of line 165-0 is now sampled in AND 169 which combines FTA, BT1, TPC, and 165-0 to set the state parity error latch 170 if the trigger 165 is not in the binary one state. Like latch 172, latch 170 remains set until reset by a master reset pulse or by a manual reset through switch 175.

If either of the parity error latches 170 or 172 manifests a parity check error, a negative potential on either lines 170-0 or 172-0 (indicating a set condition of the respective latch) will operate OR173 and inverter 174 to reset the output function buffer to a neutral state. In a traffic control situation, this will cause the traffic lights to go into a red and yellow blinker cycle until the malfunction can be remedied; either by the computer introducing a new program or by a maintenance man. The master reset pulse also resets the output function buffer.

Before turning to parity generation, it is well to digress briefly and note one fact. Even though the controller may be stepping from one state to the next and advancing the location of the state indicator shift register bit (BP5 Fields C through J) the total number of one bits will not change. Only the location of the bit will change when a state is shifted one field. There is, however, one caveat to the foregoing statement. Because of machine timing an erroneous parity check will occur when the state shifts from Field J to Field C. To obviate this difficulty, a second AND gate 161 is provided in FIG. 10. The AND 161 is activated by inputs from TPC, BT12, FTB, and the cycle complete line 241-1 (from FIG. 14) to set the trigger 165 to the one state. This setting of the parity check trigger at B12 time, in effect, makes it appear as if a binary one appeared in bit position BP12, which position is in fact unused. This corrects for the SISR-1 bit which is inserted and which would cause a double counting of the state indicator shift register bit (from Field J and Field C) during the shift.

Turning now to the parity bit generation, reference is made to FIG. 13. Parity generation is effected between the output of the tenth shift register cell CSC-10 and the delay line. The ninth shift register cell trigger 204 (FIG. 12) is coupled via lines 204-0 and 204-1 to

gates 213 and 214 (FIG. 13) which receive the TPA shift pulse on line 128A to enter each bit in trigger 215 in the same manner that the data bits are shifted into the lower order shift cells (except CSC-1). At all bit times, except when a corrected parity is to be inserted, the circuits of FIG. 13 must pass the bits from CSC-10 (trigger 215) to the delay line 233 without alteration. This is achieved by coupling the output line 215-1 through AND 233 which, except for those times when parity is to be changed, has a constant positive input on line 225A. The output of AND 223 couples through OR229 and inverter 230 to AND 231 to which a TPY timing pulse is applied on line 37-0 (from FIG. 4). Since trigger 215 stores each bit at TPA time and the TPY pulse equals the summation of TPA and TPB a one bit in CSC-10 (trigger 215) will activate AND 231 for the duration of TPY causing driver 234 to apply an input to the delay line 233. A binary zero at this time effects no entry to the delay line. Thus, a binary zero is propagated (STORED) in the delay line as a void, or lack of signal at the appropriate bit time, while a binary one is propagated as the presence of a signal at the appropriate bit time. These signals, or no signals, traverse the delay line in 111.5 microseconds for detection by the level detector 232, and entry into CSC-1 under a TPA sampling pulse, as hereinabove described.

When new parity is to be inserted, AND 223 is inhibited at A10 or C8 time by removal of the potential from line 225A. Thus, the SP or ETP bit is blocked from passing through AND 223. Reference to FIGS. 3 and 2 will reveal that at A10 time the SP parity bit is in CSC-10, and at C8 time the ETP parity bit (PF 11 in FIG. 3) occupies CSC-10. The signal to generate new parity comes from either the update state parity latch 218 or the update elapsed time parity latch 222. The former of these will be set upon the occurrence of a load signal (indicating a new program is to be loaded), or by a master reset signal or by an increment counter signal. Except for the master reset, the state parity will be updated only when a new program is entered from the computer interface, while the elapsed time parity will be updated every $\frac{1}{60}$ second, when the synch time is incremented.

The update state parity latch 218 is set by the master reset signal on line 354-1 (from FIG. 19), an FTJ control, and a TPC pulse ANDed in AND 216 to set the trigger 218. Alternatively, the trigger 218 is set by a load state function assignment signal on line 328A (from FIG. 17). The trigger 218 remains set until TPC time of B1, achieved through AND 217 with inputs from TPC and FTB (line 91A, FIG. 6). Thus, this trigger will be active at A10 time when the SP bit will be in CSC-10 and examination of the state parity condition effected.

The update elapsed time parity latch 222 is set by the master reset pulse on line 354-1 at TPC time of A1 by combining TPC, 354-1 and FTA (line 89A from FIG. 6) in AND 219 to set latch 222. Alternatively, latch 222 is set by an increment counter signal on line 143-1 (from FIG. 7) at TPA time through inputs to AND 220. As explained, the increment counter latch sets at TPC time of B3 (if it is to set). Thus, latch 222 will set at TPA time of B4. Latch 222 resets at TPC time of J1 through AND 221. Since the ETP bit occupies CSC-10 at C8 time, the set condition of latch 222 will be present at this time.

The update parity latches 218 and 222 signal the need to examine the parity of the respective data and correct it, if it is in error. Latch 218 controls the erasure or insertion of the SP bit in BP1 of Field A, while latch 222 controls the erasure or insertion of the ETP bit in BP11 of Field B. A common generate parity trigger 212 is employed for controlling both the SP bit and ETP bit testing and correction.

The generate parity trigger is reset in the unused bit periods just preceding the synch count field and the state

function assignment fields, when these bit positions occupy the shift cell CSC-10, so as to ready the trigger to determine the oddness or evenness of the count of the bits to follow. Specifically, at C9 time, when BP12 of Field B (PF12 in FIG. 3) occupies CSC-10, the combination of TPC, BT9, and FTC in AND 207 operates OR208 to reset trigger 212. Also at A11 time, when BP2 of Field A (2 in FIG. 3) occupies CSC-10, the combination of TPC, FTA, and BT11 in AND 206 operates OR208 to reset trigger 212. With the generate parity trigger reset to zero twice during each cycle of the data bits, it is complemented by each of the one data bits in each of the two groups of data fields to be checked. This is achieved by connecting the one side (215-1) of the CSC-10 trigger 215 to AND 209 which is gated by a TPB pulse. The output from AND 209 feeds gates 210 and 211 which are conditioned by feedbacks from the outputs of the trigger 212 to effect a state reversal upon each binary one in CSC-10.

With the generate parity trigger 212 reflecting the oddness or evenness of the count of the number of binary ones in Fields C through J (including the SP parity bit) and also in Fields A and B (including the ETP parity bit), and one or both of the generate parity triggers 218 or 222 set to manifest the need for examination and possible generation of a new parity bit, there remains only the function of checking and production of a new bit, if needed. The parity bits SP and ETP are residual from the previous cycle, either before loading new data, or before incrementing the counter, and they may or may not be compatible with the new data. If the total bit count (including the parity bit) is odd, the leftover parity bit is correct. If the total bit count (including the parity bit) is even, the leftover parity bit must be complemented before it enters the delay line.

Treating first the condition wherein the bit count is odd (trigger 212 in the one state), line 212-0 will be negative. This negative state will inhibit AND gates 224, 226, 227 and 228. Thus, the lack of outputs from these AND gates will produce a positive output from OR225 (with two negative inputs from AND 224 and AND 226) and negative outputs from AND 227 and 228 to OR299. Therefore, the state of CSC-10 (trigger 215) will pass AND 223 to OR299 and to the delay line without alteration at both A10 time (SP bit) and C8 time (ETP bit).

If the total bit count is even (trigger 212 in the binary zero state), line 212-0 will be positive. Thus, depending on whether the state of CSC-10 is zero or one and upon which of the update parity latches 218 or 222 is set one of the AND gates 224, 226, 227 or 228 will be active to insert or erase a parity bit. Actually, these invert the bit in CSC-10. Assuming first that the update state parity latch 218 is set, trigger 212 is in the zero state, and CSC-10 (trigger 215) stores a zero, then a binary one must be inserted. This is achieved through AND 227 which receives positive inputs from 218-1, 212-0, 215-0, FTA and BT10. With AND 227 thus activated at A10 time when the SP bit (although incorrect) occupies CSC-10, OR229 will be energized to produce a one bit pulse for entry into the delay line 233 in lieu of the incorrect zero bit in CSC-10. If the same conditions exist except for a binary one in trigger 215, then line 215-1 will be positive to activate AND 224 which has the same inputs as AND 227, except for the outputs from trigger 215. The now positive output from AND 224 produces a negative output from OR225 to inhibit gate 223 from passing on the binary one from trigger 215 during the A10 bit period. Thus, the contents of CSC-10 are effectively complemented for entry into the delay line 233.

A similar function is performed at C8 time for the ETP bit when the parity count is even. Latch 222 (line 222-1 positive) activates either AND 226 or 228 to erase or insert an ETP bit at C8 time in the same manner as described with respect to the SP bit. The OR gates 225

and 229 operate respectively, as before, to inhibit (erase) or insert the ETP bit into the delay line.

Thus, in summary, the circuits of FIG. 13 operate normally to shift the contents of CSC-10 into the delay line 233 during every bit period. When elapsed time is incremented, new state parity loaded, or a master reset occurs, parity is examined and corrected if needed. If no correction is required (parity count odd) the circuits function normally to pass on the contents of CSC-10 to the delay line. If the parity count is even, then the contents of CSC-10 are inverted before entry into the delay line.

Closure shift cells CSC-3 to CSC-5

The shift register (closure shift cells) cells CSC-3 to CSC-5 (FIG. 11) have previously been briefly described with respect to the reset thereof when they contain portions of the synch count and the elapsed time count. These stages consisting of triggers 178, 181 and 184 are cascaded by paired gates 176 and 177; 179 and 180; and 182 and 183 to provide the requisite data shift upon a TPA pulse on line 128A from driver 128 (FIG. 7). Each of the triggers 178, 181 and 184 has output connections from the zero and one sides of the trigger respectively identified with a dash "0" or dash "1." These lines are connected to FIG. 9 for ANDing with outputs from CSC-2 and CSC-6 to CSC-8 to determine the synch count, and to FIG. 15 for comparing the elapsed time count. Trigger 184 is additionally coupled to FIG. 12 to shift data to CSC-6. The three trigger stages have input lines 343A, 342A, and 341A from FIG. 18 where the loading signals are produced. When loading is to be effected, a reset is applied on line 186A followed by selective energization of the trigger set lines to establish the requisite triggers in the binary one state. Trigger 184 (CSC-5) is additionally provided with a set input 185A from OR185. Shift cell CSC-5 is used for inserting binary ones uniquely into any bit position when it is required. This is in addition to counter incrementing and parity correction. Each of the special insertion conditions will be treated when the circuits for generating the controls are hereinafter described.

Closure shift cells CSC-6 to CSC-9

The closure shift cells CSC-6 to CSC-9 consisting of triggers 194, 197, 200 and 204 (FIG. 12) follow the interconnection pattern of the cells previously described. These include the paired data transfer gates 192 and 193; 195 and 196; 198 and 199; and 202 and 203, all gated by the TPA pulse on line 128A. These stages receive data on lines 184-0 and 184-1 from CSC-5 (FIG. 11) and pass it on lines 204-0 and 204-1 to CSC-10 (FIG. 13). In addition to reset line 186A, the stages CSC-6 to CSC-8 have a reset line 326A (FIG. 17) for resetting the state function assignment bits (BP2-BP4, Fields C through J), when loading is to be effected. Each of the CSC-6 through CSC-8 cells has appropriately labelled zero and one output connections to FIG. 8 (for SC=59 detection), to FIG. 15 (for state timeout and elapsed time comparison), and to FIG. 16 (for state function assignment readout). Triggers 194, 197 and 200 also include set inputs 337A, 335A, and 333A from FIG. 18 for loading new data. Trigger 204 (CSC-9) includes the elapsed time reset line 201A, whose operation was hereinabove described, and reset lines 205A and 255A, whose functions are yet to be described.

Active state control

In several prior instances reference was made to the SISR bit in the fifth bit position of Fields C through J. It was stated that this bit position is used to mark which one of the Fields C through J is active to control the output function and the state whose timeout is being compared against the elapsed time to measure the duration of the control function. As each successive state completes its control the SISR bit is advanced one field position (except for the Fields A and B). Thus, there will be

one and only one binary one stored in the fifth position of Fields C through J. The remaining bit positions will contain binary zeros.

There are four conditions which must be examined in order to achieve a complete understanding of the active state control. These are:

(a) Normal data cycling wherein the elapsed time is less than the stored state timeout of the active state.

(b) Control advance from one state to the next following state, wherein the latter state is used (state timeout is not zero).

(c) Control advance from one state to the next following state wherein the latter state is unused (state timeout is zero).

(d) Control advance from the state in Field J to the state of Field C so as to prevent misoperation upon Fields A and B.

For the first of the foregoing conditions, it will be assumed that Field F contains the active control state, that the event is not completed, and that the state timeout in Field G is zero. For these conditions precedent, and the data cycling continuously through the shift register, the line 276A (FIG. 14) will be negative at H1 time during the cycle, when BP6 through BP12 of Field G occupy CSC-2 to CSC-8. This line will otherwise be positive at all other BT1 times (in the example chosen). The state timeout latch 236 will remain in its reset condition because the elapsed time has not yet equalled the value of the state timeout of Field F.

The active state present latch 247 (FIG. 14) sets at BT9, TPC of the field time of the field containing the SISR bit and resets at BT8 of the next field. For the chosen example, latch 247 sets at F9, TPC time, and resets at G8, TPC time. This setting of latch 247 is controlled by the presence of the SISR bit in CSC-5 at BT9 (F9 in the instant case). To prevent a bit in either Field A or B from setting latch 247, the lines 116-0, 119-0, and 122-0 enter OR244 which yields a positive output while Fields C through J pass through the shift register. This is so because the field counter is reset to 0000 for Field A, and is stepped to 0001 for Field B. Thus, for Fields A and B, the three high order triggers of the field counter will remain reset, to yield positive inputs to OR244. At all other field times one or more of the inputs to OR244 will be negative to produce a positive output therefrom. The positive output from OR244 when combined with BT9, TPC, and the line 184-1 (positive at F9), in AND 245 sets latch 247. Reset of latch 247 is through AND 246 which combines BT8 and TPC to reset latch 247 at G8.

When latch 247 sets at F9, TPC time, it immediately combines its positive output on line 247-1 with BT9 and TPC in AND 248 to load the function buffer with the state function assignment bits (SFA) in BP2 to BP4 of Field F. From the timing charts (FIGS. 2 and 3) it will be noted that this data is present in CSC-6 to CSC-8 at this time. Actually the identical data is already present in the buffer, and therefore, does not change. This invariable loading of the function assignment from the active field does no harm and results in certain circuit economies. When, however, the state advances, a new state function assignment will be loaded.

With latch 247 set from F9 to G8 of every data cycle, the advance state latch 254 will not set, as it ought not to. It can only set at BT1 time if the active state latch 247 is set and the line 237A positive. Since the state timeout latch 236 will not set because timeout has not been achieved, and since line 276A is positive at all BT1 times except at H1 time when latch 247 is reset, the coincident conditions necessary to operate AND 252 and set latch 254 are not present. It, therefore, will remain reset. Since latch 254 remains reset, none of the operations incident to an advance in state will be initiated, with but one slight reservation.

With latch 247 set from F9 to G8 and latch 254 re-

maining reset, lines 247-1 and 254-0 will both be positive at G1 time. Therefore, at G1 and TPB AND 251 will yield a negative response on line 251A to reset the state timeout buffer (FIG. 15). Immediately thereafter at TPC time, AND 249 yields a negative output to inverter 250 to apply a load control signal on line 250A to reload the state timeout from Field F into the state timeout buffer (FIG. 15). At G1 time, BP6-BP12 of Field F occupy CSC-2-CSC-8 of the shift register and is thus available for loading.

The net result of the normal cycling of the active state through shift register is the reloading of the active state function assignment and the active state timeout in their respective buffers. When, as will be seen in the explanations to follow, the active state bit advances the loading will proceed from the next active state.

The next condition to be examined is that wherein the state timeout equals the elapsed time, and the next following field is an active field. For this example, it will again be assumed that Field F contains the active state, but unlike the previous example, Field G will contain an active control state with a state timeout other than zero. In this instance, all of the circuits of FIG. 14 will be active.

Proceeding in the order of the sequence of events, the first event is the setting of the state timeout latch 236 at at B10 time. As was explained with respect to FIG. 8, the SC=59 latch 149 will set at A10 and the SC=59 delay latch 152 will set at C1 time. Therefore, between A10 and C1, specifically at B10, lines 149-1 and 152-1 will both be positive. So also will the line 274A be positive since this comes from a comparator that compares each successive group of seven bits with the stored timeout. While other combinations of bits might produce a false comparison, by sampling the comparator only at BT10 time, when the ETC bits are in position (in CSC-2 to CSC-8) to compare, misoperation is prevented. Thus, at B10, TPC time, with the assumed conditions, AND 235 is activated to set the state timeout latch 236. This latch will remain set until G1 time.

Latch 247 will set at F9, TPC time, as previously described, and will reload the state function assignment from Field F in the state function buffer. It will also reset the state timeout buffer as before, but it will not now load it. This is because the setting of the advance state latch intervenes. With latch 236 set and latch 247 set before G1 time, AND 252, having inputs from 237A, 247-1, 315-0 (now, and normally positive), BT1 and TPB, sets latch 254. Before it switches, however, AND 251 operates to provide the reset pulse for the state timeout buffer on line 251A, as hereinabove described. When latch 254 sets at TPB time, it removes the positive potential from line 254-0 to inhibit AND 249 to prevent reloading of the state timeout buffer, which remains reset until it is loaded from Field G.

Whether or not the state timeout buffer is reset without reloading is of no consequence. Once the state timeout latch 236 is set, the advance state latch 254 will invariably set to cause an advance to the next state. Once the next state with a state timeout other than zero is located, the state timeout buffer will be again reset and loaded with the new state timeout for that state. This will occur within one data cycle, and since the timeout comparison will have been terminated by C1 time, and, in the example chosen, will have already been terminated, then there is at least one second before the data in the state timeout buffer is used for comparison. By this time it will have been properly reset and loaded.

Setting of the advance state latch 254 also causes the advancement of the SISR bit from Field F to Field G. This is achieved by erasing the one bit in Field F by resetting CSC-9 to zero, and by inserting a one bit in Field G by setting CSC-5 to the one state at the requisite time. The erasure is achieved at G1 time while latch 254 is still set (it resets at G10), through combining 254-1, BT1, and TPC in AND 255 to apply a negative potential to line

255A, which line in FIG. 12 resets trigger 204 (CSC-9). At G1 time it will be noted that BP5 of Field F resides in CSC-9 (see FIGS. 2 and 3). The insertion of the SISR bit in Field G is accomplished at G9 time when BP5 of Field G occupies CSC-5. The positive potential of 254-1, when ANDed with TPC, BT9, and line 88A (now positive) in AND 256 yields a positive potential on line 256A, which in FIG. 11 operates OR185 to set trigger 184 to insert the one in Field G.

When at G1 time AND 255 operated to erase the SISR bit in Field F, it also reset the state timeout latch 236. Latch 254 sets automatically at G10 time (and TPB) through AND 253. There remains now only the loading of the state timeout buffer and the state function assignment from Field G.

With SISR bit now in BP5 of Field G (inserted at TPC time of G9), the active state latch 247 will set immediately upon the insertion thereof. This will operate AND 248 at G9 (TPC time) to load the state function assignment from Field G overriding the storage of Field F's SFA bits therein. Latch 247, set at G9 (TPC) finds latch 254 reset (at G9, TPB time). This condition persists at H1 time when AND 251 operates to reset the state timeout buffer (still reset from G1 time) at TPB time. Immediately at TPC time, AND 249 operates to load the state timeout buffer from CSC-2 to CSC-8 where the state timeout bits for Field G now reside.

Since latch 236 reset at G1 time and it has been assumed that the state timeout is other than zero the advance state latch 254 remains reset. Field G now exercises its control in the same manner as that described for Field F, except for the occurrence of events one field position later.

If, instead of containing a state timeout in excess of zero, Field G were unused, as manifested by a state timeout of zero, then all of the operations just described with respect to the advance out of Field F would still obtain. However, when it was attempted to give control to Field G, the existence of the state timeout of zero therein would cause an advance to Field H. A state timeout of zero in Field G will produce a negative potential on line 276A at H1 time. This control (via OR237 and line 237A) will set the advance state latch at H1, TPB time, to inhibit the loading of the state timeout buffer at TPC time through inhibiting AND 249 which requires latch 254 to be reset. This alternative setting for the advance state latch 254 erases the SISR bit in Field G, writes a one in BP5 of Field H and advances the control to Field H, just as if a state timeout had occurred in Field G. If Field H were unused, the control would advance to Field J and so on. Since control can be passed within one field time, the shift is executed within approximately 12 microseconds. Thus, in the worst case, the skipping over unused fields can be achieved long before the next synch pulse requires new action.

The final condition meriting attention is that wherein the control shifts from Field J to Field C. Here the problem is one of skipping over Fields A and B while still retaining the control field. All of the previous functions described with respect to Field F will also apply to Field J. The active state present latch 247 will load and reload the state function assignment every cycle at J9 time. The active state present latch in the absence of an advance state condition, will reset and immediately reload the state timeout buffer from Field J at A1 time. When a state timeout for Field J occurs, the advance state latch 254 will set to inhibit the reloading of the state timeout from Field J, and will control the erasure of the SISR bit from Field J. The insertion of a one bit into Field A will be inhibited because at BT9 (when the bit would normally be inserted), line 88A is negative to inhibit AND 256 from writing in a one bit in BP5 of Field A. Since gate 254 will reset at A10 (in this instance) Field B is protected by the reset.

There still remains the insertion of the SISR bit in

Field C. This is achieved by using the cycle complete latch 241. This latch will set upon an advance state condition at field time A. Line 255A, negative at BT1 and TPC of the field time following the active field, is inverted in NOT 240 and ANDed with FTA in AND 238 to set the cycle complete latch 241. This latch sets at A1, TPC time and resets (through AND 239) at D1 and TPC time. With the cycle complete latch 241 set, line 241-0 is negative to yield a positive output from OR242 from FTA to FTD. Therefore, at C9 and TPC, when AND gate operates, line 243-4 is pulsed to write in the SISR-1 bit (BP5 in Field C) by pulsing OR185 (FIG. 11) to set trigger 184 (CSC-5). This acts simply to delay the writing in of the SISR bit. With Field C now containing the requisite control bit, it operates as did the fields hereinabove described.

State time out storage and detection

In the prior discussion of FIG. 14, reference was made to the state timeout buffer, to the detection of state timeout equals zero, and to the loading and resetting of the state timeout buffer. The circuits for achieving these functions are shown in FIG. 15.

The detection of a state timeout of zero is achieved by ANDing the zero outputs of all the triggers constituting CSC-2 through CSC-8 in AND 275 and inverting in NOT 276 to produce the positive control exploited at BT1 in FIG. 14. It is only at BT1 time of Fields A and D through J, that the state timeout bits will occupy these shift register positions. While other bit combinations might equal zero and produce an output on line 276A, this false output is inhibited from setting the advance state latch 254 (FIG. 14) by sampling the condition of line 276A only when it can contain a legitimate zero test.

The state time out buffer consists of seven bistable latches with odd-numbered legends from 277 through 289. Each of these latches has connections to a common reset line 251A which is potentialized as hereinabove described. Each latch has a corresponding AND gate in the even-numbered series from 278 through 290. These AND gates have connections to a common load control 250A potentialized by the circuits of FIG. 14, as previously described. Each of the AND gates has a connection to the one output line of the triggers constituting the shift cells CSC-2 through CSC-8, connected as shown in FIG. 15. When the line 251A is pulsed at TPB time by the circuits shown in FIG. 14, the latches 277 to 289 (odd-numbered only) will reset to the zero state. When the line 250A is pulsed at BT1, TPC time, the STO bits from the field then occupying the shift register positions CSC-2 to CSC-8 will be passed by the AND gates 278 to 290 (even-numbered only) to set the respective triggers to manifest the state time out.

The remaining function performed by the circuits of FIG. 15 is the comparison of the state timeout with the elapsed time count in BP3 to BP9 of Field B. This is achieved by comparing the stability state of each of the storage latches constituting the state timeout buffer with the stability state of the corresponding trigger of the shift register cell. For example, the latch 277 storing the highest order binary bit of the state timeout, is compared with the trigger 139 (FIG. 7) constituting the CSC-2 shift register cell. This is achieved by combining the binary zero line 139-0 from the CSC-2 trigger 139 (FIG. 7) with the binary one line 277-1 from the corresponding storage latch in the AND gate 257. This gate will yield positive output if there is a zero in the shift cell CSC-2 and a one in the buffer latch. To provide a mismatch signal for the reverse situation AND 258 combines 139-1 and 277-0 to yield a positive output upon a miscomparison. If either AND 257 or AND 258 yields a positive output, indicating a mis-match in the high order position, OR261 will yield a negative response on line 274A. By a similar combination of connections in the lower orders in the paired AND gates 259 and 260; 262 and 263; 264 and 265; 267 and 268; 269 and 270; and 272 and 273,

one or more of the OR gates 266, 271 or 274 will yield a negative output upon a miscomparison. The outputs from these OR gates, when commoned in the line 274A will produce a positive potential thereon only upon a total comparison in all compared bit positions. The paired AND gates for each comparison order perform the equivalent EXCLUSIVE OR function.

Output function buffer and output function register

In the description of FIG. 14, it was shown how a load in the state function assignment buffer was generated on line 248A during the cycling of the active state through the shift register, to load the output function buffer, even though it already contained the same data. This is achieved in FIG. 16 by inverting the negative response on line 248A in NOT 291 and coupling its output to the paired AND gates 292 and 293; 295 and 296; and 298 and 299. These gates pass the zero and one line potentials from the corresponding triggers in the shift register to establish the latches 294, 297 and 300 in the respectively corresponding binary zero or one state.

Storage latches 294, 297 and 300 are provided with paired zero and one output lines which connect through paired gates 301 and 302; 304 and 305; and 307 and 308 to triggers 303, 306 and 309. These triggers control the activation of the final work circuits, for example, the lighting of the appropriate traffic lights corresponding to the combination of potentials on the output lines 303-0, 303-1, 306-0, 306-1, 309-0 and 309-1. These lines would normally activate a decoding circuit, as for example, a relay tree, to provide a different control function. The output function register is reset by a negative potential on line 174A produced by the circuits of FIG. 10. As explained with respect to that figure, this reset occurs when a parity check produces an error or upon a master reset (yet to be explained). The result of this reset of the output function register is to establish the controlled apparatus in a neutral or standby condition until the malfunction can be corrected. In the case of a traffic controller, this sets the traffic lights to a blinker status wherein the main thoroughfare flashes a yellow light and the secondary streets flash a red light.

The loading of the output function register from the output function buffer is achieved by pulsing line 157-0, the paired entry gates responding only to a negative-going transition (denoted by the full white arrowhead). Thus, the output function will be loaded into the output function register upon every transition of the synch time latch 157 (FIG. 8) from the binary zero to the binary one state wherein the line 157-0 undergoes a negative-going potential change. Actually, this loads the output function register every sixtieth of a second, but since the contents of the output function buffer do not change this frequently, the output function register is merely reloaded with the same data it already contains. When, however, the synch count is 59 and the state timeout equals the elapsed time count, a new entry is made into the output function buffer at the state timeout duration minus one-sixtieth of a second. When the synch count experiences the next transition (sixty sixtieths) so that the ETC=STO, the output function buffer is loaded with the new output function. This insures that the change in output function is synchronized with the sidereal time (60 cycle) and prevents the accumulation of errors previously alluded to.

Loading a new program

To complete the explanation of the operation of the controller, there remains only the functions of loading a new program and the master reset. The former of these functions is performed by the circuits of FIGS. 17 and 18.

Before proceeding with a detailed examination of these circuits, it is well to re-examine some of the conditions incident to a new loading. The first condition is that a computer will determine that a new program is to be instituted. In the traffic control application this results from

an analysis of the traffic flow in the controlled area and a computation of the traffic signal pattern for each remote controller. The computer will have stored the previous program for each separate controller and will choose a new program for loading that is compatible with the prior program. Specifically, this means that the last scheduled function in Field J of the program (or the last active field) can be followed compatibly by the function to be loaded into Field C of the new program. A further condition is that the computer alerts the controller to the need for a new program, but that loading does not proceed until the controller steps through Field J. The controller then, in effect, operates as a master to extract the data from the computer interface, which is slaved to the controller for loading purposes.

The computer interface 13 has the capability of communicating with an electronic data processing system on a time-sharing basis. When the remote computer wishes to load a new program, it first lowers the potential of the select line 13-1. This charge operates gate 310 to set the select trigger 312 to alert the controller. The select line 13-1 may then return to its original state. When the controller has completed its control cycle and is about to advance out of Field J, the cycle complete line 241-1 becomes positive (specifically at A1 time). This condition together with the set condition of the select trigger 312 and a TPC pulse operates AND 313 to set the ready latch 315. Loading may now begin.

The ready latch 315 performs the following functions:

- It inhibits further state advance, and keeps the SISR bit in the first state (Field C).
- It informs the interface unit that the controller is ready to load a new program.

The first of the foregoing functions is achieved by connecting the 315-0 line (now negative) to AND 252 (FIG. 14) to prevent the setting of the advance state latch 254. This prevents any further advance and locks the SISR bit in Field C.

The second function results from the positive condition of line 315-1 which is returned to the interface unit 13 (FIG. 17). The interface is now advised that the controller is ready to receive data.

When the interface unit 13 receives the ready response on line 315-1, it potentializes the respective lines of the cable 13A with a positive potential to manifest the binary ones, and with a negative potential to manifest the binary zeros in the state function assignment and state timeout for Field C. It will be noted that this data occupies ten bit positions in each field yet in FIG. 18 there are only seven shift register positions into which data is loaded. This difficulty is obviated by loading the function assignment in parallel at one bit time into CSC-6 to CSC-8 and loading the timeout in parallel into CSC-2 to CSC-8 at a different bit time when these respective data should occupy these shift register positions. Specifically, when the ready latch 315 sets at A1 time and the interface 13 responds by potentializing the respective lines in the cable 13A and applying a positive potential to the service request line 13-9 indicating that the interface is set to deliver. Line 13-9 when combined in AND 317 with the line 244-A (positive from C1 through J12 as previously explained), line 315-1, BT9, TPB, and line 204-1 from CSC-9 will set the load latch 319 at C9 time when the SSL1 bit (a binary one) of Field C occupies CSC-9. The SSL1 bit is inserted into Field C at the termination of the loading operation, as will be explained. The setting of load latch 319 applies positive potential to line 319-1 to operate AND 326, together with BT9 and TPB to reset the state function assignment for Field C now present in CSC-6 to CSC-8 by potentializing reset line 326A to reset triggers 194, 197 and 200 (FIG. 12). Immediately thereafter at BT9 and TPC, AND 327 operates through NOT 328 to apply a positive potential to line 328A. Line 328A in FIG. 18 operates AND gates 332, 334, 336 to pass any positive potentials on lines 13-8A, 13-7A and 13-6A to OR gates 333, 335, and 337 respectively to set the respec-

tive triggers of CSC-8, CSC-7 and CSC-6 to load the SFA of Field C. The final event that occurs at BT9 is the erasure of the SSLI bit in Field C, this bit being used to sequence the loading from field to field as the SISR bit controls the sequencing when the controller is advancing the states. This erasure results from operation of AND 324 by the combined potentials of line 319-1, BT5, TPC, and the absence of Field J (line 106A). Line 324A, thus potentialized at BT9 time operates OR205 (FIG. 12) to reset trigger 204 (CSC-9) which now contains the SSLI bit for Field C. This relinquishes control of Field C. There remains, however, the loading of the state timeout for Field C and the insertion of an SSLI bit in Field D.

The loading of the state timeout comes from AND 329 which has inputs from 319-1, BT1, and TPC to operate NOT 330 to apply positive potential to line 330A, which line in FIG. 18 conditions AND gates 338 through 344 to pass the positive potentials of lines 13-2 through 13-8 (in inverse correspondence) to the directly corresponding binary one loading lines of CSC-2 through CSC-8. The loading of CSC-6 through CSC-8 proceeds through OR gates 333, 335 and 337 which also pass the load signals for the SFA bits. It is noted that at BT1 time, BP6 through BP12 occupy the stages CSC-2 to CSC-8. The final operation of inserting an SSLI bit in Field D proceeds from AND 325 by combining 319-1, BT5, TPC and NOT FTA (line 88A). Line 325A thus potentialized, operates OR185 (FIG. 11) to set trigger 184 (CSC-5) to the one state. At BT5 time CSC-5 contains the SSLI bit. The operations with respect to Field C are now complete and Field D has been activated to assume control. The interface 13 must now be appraised of this condition.

The last operation with respect to Field C was completed at BT5, FTD time. At BT6, FTD time (when loading is to be shifted from C to D), the service response latch 323 (FIG. 17) is set through AND 321 by combining 319-1, BT6, and TPA. This latch 323 through line 323-1 signals the computer interface that the data on the data cable 13A has been loaded. Line 323-1 also resets load latch at TPB time of the same bit period. When the computer interface receives the service response signal on line 323-1, it depotentializes the service request line 13-9, which through NOT 331 and AND 322 (together with TPC) resets the service response latch 323. The controller is now in the same condition as it was when the loading of Field C was initiated.

When the SSLI bit which was inserted into Field D reaches CSC-9 at D9 time, the load latch 319 will set to repeat the sequence of operations hereinabove explained with respect to Field C, to thus load Field D and write an SSLI bit into Field D. This successive loading of each field continues until Field J is loaded. This loading of the fields may include loading state timeouts equal to zero in the event that eight successive events are not required. This does not affect the loading operation in any manner, although it does produce field skipping when the controller returns to control the output functions. Since the computer is presumed to have a high degree of computational ability, it will always produce a compatible load for each controller.

When the loading of Field J is initiated at J9 time, AND gate 324 will be inhibited by the presence of a negative potential on line 107A. Therefore, the SSLI bit in Field J will not be erased. The result of this retention of the SSLI bit in Field J is that if the interface unit 13 should produce more than eight program steps, the loading will continue in Field J which will store the last program data in excess of seven.

When the interface unit 13 has completed its loading, which load, although it must start with Field C may be less than a total load, it stops the service request signals on line 13-9, and applies a negative pulse to the operate command line 13-10 to reset the select trigger 312 through gate 311. Trigger 312 resets the ready latch 315 through AND 314 at A1 and TPC time to restore control to the controller. Since no data in the delay line

storage is destroyed unless it is replaced with new data the computer interface 13 can load new data into less than the eight fields. When it does so, the SSLI bit remains in the field following the last field to be loaded, including Field J for the reasons hereinabove explained.

5 When the ready latch 315 resets and line 315-0 becomes positive, AND gate 316 becomes operative at BT9, TPC time, of Fields C through J to erase all SSLI bits by resetting CSC-9 at the time when such bits would occupy that storage cell. Additionally, line 315-0 operates AND 320 at C5, TPC time, to insert an SSLI bit in Field C in anticipation of a future loading operation. This erasure and insertion operates every cycle during the normal operation of the controller.

10 15 When the operation of the controller is restored by the resetting of the select trigger 312 and ready latch 315, the controller resumes operation under the control of the SISR bit in Field C which bit was permitted to be inserted when the controller reached a state timeout in Field J but the advance was prevented by the intervention of the loading operation. It will be noted that the synch count and elapsed time count were not reset during the loading operation and were permitted to increment. Thus, even during loading the synchronism with 20 the sidereal time is not lost, loading being accomplished well within the time between time changes. Thus, there is 25 no need to change the elapsed time parity. The state parity, however, must be checked and updated. To this end the load signal for the state function assignment (on line 328A) also connects in FIG. 13 to set the update state parity latch 218 to maintain the parity integrity during loading. Also during loading, the output function register retains the state function assignment from Field C (state A) of the previous program. When control is 30 restored and the synch count steps to 62, the control advances to Field C which enters the SFA from that 35 state into the register.

Master reset

40 The final operation of the controller is a manually induced one. This master reset would seldom be used, but is provided in case of system malfunction. In such instance, the maintenance engineer, having corrected the malfunction would depress the master reset switch 345 (FIG. 19) to reinstate operation of the controller. Depression of this switch applies ground (relatively negative) potential to line 345-1 to set the reset latch 348. As soon as the first bit of Field A enters the closure (at A1, TPB time) AND 352 operates to set the master 45 reset latch 354. Thereafter at A1, TPD time, the master reset interlock latch 351 is set through AND 349. Since latch 351 sets at TPD of A1 time, it cannot reset latch 354 until TPB of the next following A1 time. Latch 351 resets latch 348 when master reset switch 345 is released through NOT 346, AND 347, at TPA time. This 50 sequencing of the latches provides only one operation per depression of the master reset switch.

55 With the master reset latch set for one complete cycle of data through the shift register (from A1, TPB to A1, TPB of the next cycle), the following operations are effected:

- (1) It sets the update state parity and update elapsed time parity latches (FIG. 13).
- (2) It erases the data bits in storage (FIG. 7).
- (3) It resets the state parity error and elapsed time parity error latches (FIG. 10).
- (4) It resets the output function register to zero, the null standby function (FIGS. 10 and 16).
- (5) It inserts a binary one in the SISR position in Field C (FIG. 14).
- (6) It resets the select trigger to prevent loading of new data from the interface (FIG. 17).
- (7) The SSLI bit is inserted in Field C (FIGS. 17 and 11).
- (8) It inserts a state parity bit in BP1 of Field A.

Each of the foregoing operations will be separately described.

The setting of the update parity latches 218 and 222 (FIG. 13) is achieved through the positive potential of line 354-1 being present at FTJ and TPB time to operate AND 216 to set latch 218 and at FTA and TPC time to operate AND 217 to set latch 222. This operates to correct the parity because the data contents of the delay line are to be erased.

The erasure of the data bits in storage is achieved through the negative potential on line 354-0, which in FIG. 7 exhibits AND 129 to prevent all binary ones from entering the CSC-1 delay latch 130. This effectively passes all zeroes into the shift register positions beyond CSC-1. Since the master reset latch sets at A1, TPB time and resets one cycle later, this is effective to erase all of the pre-existing bits in the storage.

The reset of the parity error latches originates with the negative polarity status of line 354-0 in FIG. 10 which operates directly on the reset OR inputs of the state parity error latch 170 and the elapsed time parity error latch 172. This potential will maintain these latches reset for the duration of the master reset cycle.

The same master reset latch line potential in FIG. 10 operates OR173 to produce (through NOT 174) the requisite negative reset potential on line 174A to reset the output function register (FIG. 16) and hold it in the reset condition. As previously explained this produces a standby or null condition in the output work circuits (blinkers at a traffic intersection).

The insertion of the SISR bit in Field C is necessary to set Field C as the potentially active field when new data is loaded into the controller following the master reset cycle. This is achieved by the negative potential on line 354-0 in FIG. 14 which operates AND 243 at C9 time to insert the bit in Field C in CSC-5, as previously described in typical control advance cycle. At C9 time BP5 of Field C occupies CSC-5 where all individual data bit insertion (except parity) occurs.

Should a loading operation be in progress during a master reset operation, the negative potential on line 354-0 in FIG. 17 will immediately reset the select trigger 312. This will reset the ready latch at the next A1 time to insert the SSLI bit in Field C as previously described as an incident to reset of the ready latch. This prepares the controller to start the loading of a new program in Field C upon completion of the master reset cycle.

Since it is known that the data in storage is to be reset to zero, it follows that the state parity bit must be a binary one in order to preserve the parity integrity. Therefore, to insure that no state parity error will be produced when the master reset cycle is terminated, the SP bit is inserted. This is effected in FIG. 19 by the positive condition of line 354-1 together with A5 and TPC in AND 355 to set the CSC-5 trigger 184 at A5 when this cell contains the SP bit. This is necessary because at A1 time when the master reset latch 354 was set, the generate parity trigger was already operating to count the bits in the state fields.

When the data has completely traversed the shift register once, the presence of the master reset interlock latch 351 (line 351-1 positive) coupled with A1 and TPB in AND 353 resets the master reset latch 354. The master reset interlock latch 351 also resets at TPB, but not before the conditioning potential for the reset of latch 354. The controller now returns to control over the output functions. However, since it is empty, it will find state timeouts of zero in all state fields and will recycle without changing the output function. When the computer, alerted by the maintenance man (by means not shown), transmits a new program, the controller will accept the load and resume normal operation.

An alternative to the more stringent master reset control which may be exercised by the maintenance engineer is the depression of the parity error indicator switch 175

(FIG. 10). This switch, when depressed will reset the parity error latches 170 and 172 and provide the controller with a chance to correct itself. If it generates no further parity errors, then it will be permitted to continue in operation with the existing program. If the errors persist, then the master reset cycle can be initiated following appropriate maintenance.

Summary

In the foregoing detailed explanation, it was explained that the synch time stored in Field A of the circulating data was incremented each sixtieth of a second from the commercial power supply. When this count equalled 59 the stored timeout for the event then in progress was compared with the elapsed time in Field B, which elapsed time is always reset to one second. If the two were equal, the state control advanced to the next active field under control of the SISR bit. If the count were unequal, the elapsed time count would be incremented by one count. If a state field were unused, it contained a zero timeout which caused rapid skipping to the next active field. During the cycling of data, parity is continually checked, and new parity generated when the fields to be checked change their data content either by incrementing the elapsed time count or by loading in new data. By resetting the elapsed time count to one second and looking for a comparison at $59\frac{1}{60}$ second the change from one state to the next may be synchronized with the commercial power supply to effect the advance upon the next synch count.

When loading is to be effected, it always proceeds from Field C forward, and may include all eight data fields or any lesser number. During loading, the active state is shifted to Field C of the old program, but the output function register retains the function assignment of the last active field of the old program. With a basic period of 120 microseconds the new program data for state 1 is loaded into Field C before the expiration of the $\frac{1}{60}$ second when the contents of the output function buffer are transferred to the output function register. Thus, the new data for Field C is available well in advance to permit entry thereof into the output function register to continue the uninterrupted control of the output functions in synchronism with sidereal time. The remaining data can be loaded leisurely while the new state 1 control is active, since the minimum timeout for any state is 1 second (except if it is unused). Field C, however, is always a "used" state. Thus, the loading of at least Field C may be achieved before the next transition of the sixty cycle line. This provides synchronous operation between two differently timed synchronous circuits at the critical transition times.

The only time that the system loses synchronism with the commercial power line is upon equipment failure (parity error), when a reset operation is manually introduced.

From the foregoing, it will be apparent that by simple expansion, both the number of state fields and the number of different functions can be expanded. So also can the time intervals be expanded to include a minutes counter, if such be desirable. The main design criterion that must be preserved is that the ratio of the minimum sidereal time interval to the electronic data cycle time must be large enough (it is 138 in the present embodiment) to insure that all of the necessary data processing can be completed within one sidereal time interval.

While the invention has been particularly shown and described with reference to a preferred embodiment thereof, it will be understood by those skilled in the art that various changes in form and details may be made therein without departing from the spirit and scope of the invention.

What is claimed is:

1. Apparatus for controlling the sequence and respective durations of a plurality of electrically controllable work functions comprising:

- (a) a serially organized digital memory having serially ordered storage positions storing digital manifestations of each of a sequence of work functions to be performed, in combination with the respective time durations of each of said work functions, and digital manifestations of the elapsed time of the work function in progress; 5
  - (b) means for cyclically and serially accessing all of the digital manifestations in said digital memory in succession; 10
  - (c) separate digital storage means for storing digital manifestations of the work function in progress and its scheduled time duration; 15
  - (d) a sidereal time generator operative to produce a time pulse denoting each one of an uninterrupted succession of time intervals of equal and predetermined duration; 15
  - (e) means responsive to said time pulse during the cyclical and serial accessing of said data for incrementing the digital manifestations of the elapsed time of the work function in progress by one count; 20
  - (f) means responsive to the incrementing of the said digital manifestations for comparing the thus-incremented manifestations with the digital manifestations of the time duration stored in said separate storage means and yielding a comparison signal upon equality; and 25
  - (g) means responsive to said comparison signal and to the next occurring time pulse for immediately entering the digital manifestations of the next successive scheduled work function and its scheduled time duration from said digital memory into said separate digital storage means, and for resetting the digital manifestations of the time duration in progress to begin a new time accumulation. 30
2. The apparatus of claim 1 wherein said means for cyclically and serially accessing the digital manifestations in said memory has a cycle time which is substantially shorter than the sidereal time interval. 35
3. The apparatus of claim 1 wherein additional means are provided for detecting a scheduled time duration of zero, and said means responsive to said comparison signal is additionally responsive to said zero scheduled time detecting means for skipping over unused work function scheduling storage positions whereby a sequence of work functions less than the storage capacity of the digital memory may be scheduled. 40
4. The apparatus of claim 1 including means for generating a parity bit in response to a change in the data content of said memory. 50
5. The apparatus of claim 4 including means for checking the parity of the data upon each cyclical access thereto and for setting the separate work function storage means to a predetermined storage manifestation in response to a parity check error. 55
6. Apparatus for controlling the sequence and respective durations of a plurality of electrically controllable work functions comprising:
- (a) a delay line memory having an input terminal and an output terminal and operable to transmit binary data manifestations between said terminals with a substantially constant transit time; 60
  - (b) a shift register having a plurality of cascaded orders connected between the terminals of said delay line to provide a closed data transmission loop; 65
  - (c) a clock pulse generator operably connected to said delay line memory and to said shift register to synchronize the flow of data in said loop; 70
  - (d) a counter operably connected to said clock pulse generator to count the progression of data bits in said loop and to provide signals manifestive of the identity of the bits in the respective ordered positions in said shift register; 75
  - (e) means under control of said clock pulse generator and said counter for entering binary data into said

- shift register for insertion into the circulating stream of data in said loop, the entered data, upon completion of the loading, consisting of a plurality of serially disposed data fields, each containing a like number of data bit positions, at least one of which fields is allocated for the accumulation of the elapsed time of the function in progress, and the remaining fields containing in corresponding bit positions thereof binary manifestations of the successive work functions to be scheduled and the respective durations thereof, each of these latter fields containing a bit position for the recording of a binary marker bit which signifies the data field which is active to control the work function, the first only of these latter fields having the marker bit present upon completion of the loading;
  - (f) a function control buffer;
  - (g) a function control output register;
  - (h) an active function duration buffer;
  - (i) means under control of said counter, said marker bit, and said clock pulse generator for loading the function control data from said shift register into said function control buffer upon every circulation cycle of the data in said loop when the active output function bits, as manifested by said marker bit, are present in the respective orders of said shift register;
  - (j) means under control of said counter, said marker bit, and said clock pulse generator for loading the active function duration data from said shift register into said active function duration buffer upon every circulation cycle of the data in said loop when the active function time duration bits, as manifested by said marker bit, are present in the respective orders of said shift register;
  - (k) a sidereal time generator operative to produce a timing pulse at equal predetermined time periods;
  - (l) means responsive to each sidereal time pulse under control of said counter and said clock pulse generator for incrementing the elapsed time count in said at least one data field by one count, as said elapsed time shifts through said shift register;
  - (m) a comparator operative to produce a comparison signal upon the equality of the data entered therein for comparison;
  - (n) means responsive to the incrementing of said elapsed time count and operative under control of said counter and said timing pulse generator for comparing in said comparator the bits manifesting said elapsed time count with the bits stored in said active function duration buffer, when the elapsed time bits occupy the respective orders of said shift register;
  - (o) means responsive to said comparison signal, when the elapsed time equals the stored duration, upon the occurrence of the next sidereal pulse for erasing the marker bit in the prior field and inserting it in the next following field, resetting the elapsed time count to a count of one, and entering the new output function from said output function buffer into said output function register, whereby the precession of the marker bit from one field to the next causes entry of the next function data into the function buffer and the entry of the next function duration data into the duration buffer.
7. The apparatus of claim 6 including:
- (a) means for checking the parity of the data bits as they enter the shift register and setting said output function register to a predetermined numerical condition responsive to a failure in the parity check.
8. The apparatus of claim 6 including:
- (a) means for generating and inserting into predetermined positions in said data stream parity bits in response to a change in the content of the data for which the parity bit is generated.
9. The apparatus of claim 6 including:

(a) means responsive to a stored function time duration of zero in any data field for erasing the marker bit in that field and inserting the marker bit in the next following function control field, whereby less than the total storage capacity of the apparatus may be utilized by loading the unused function control fields with zero data bits.

10. Apparatus for controlling the sequence and respective durations of a plurality of electrically controllable work functions comprising:

- (a) a recirculating memory loop including a delay line and a shift register having data bit manifestations circulating continuously therein, the said data bits being organized into a plurality of serially arranged data fields of a like number of bits, at least one of which fields contains bits manifestive of the elapsed time count of the active work function and the remaining fields contain data bits manifestive of the successive work functions and their respective time durations, each of said latter fields having a bit position allocated for the recording of a marker bit to denote the active work function;
- (b) a time pulse generator;
- (c) means responsive to said time pulse generator during the recirculation of the data in said memory for incrementing said elapsed time count by one count upon each pulse from said time pulse generator;
- (d) means operative during the circulation of the data in said loop for comparing the elapsed time of the active work function with the scheduled duration of that work function and producing a control signal upon the equality thereof;
- (e) means responsive to said control signal for moving said marker bit from its position in the field of the active work function to a corresponding bit position in the next following serially arranged data field and resetting the elapsed time count, thereby marking the data bits in said next following data field as a new work function serving as the active function, and initiating an elapsed time count for the new work function;
- (f) and means under control of said marker bit for registering the active work function.

11. Apparatus for controlling the sequence and duration of a plurality of electrically controllable work functions comprising:

(a) means storing digital manifestations of each of the work functions to be controlled together and in juxtaposition with digital manifestations of the duration of each of the respective work functions;

(b) means for counting time increments;

(c) marker means in said storing means for marking the active work function;

(d) means under control of said marker means for comparing the manifestations of the duration of the active function with the count in said means for counting time increments;

(e) means operative in response to an equality between the time count and the duration of the active function for resetting the time count and moving said marker means in said storing means to a position to mark the next scheduled work function as the active function;

(f) and means under control of said marker means and the digital manifestations of the marked active function for registering the active function.

12. The apparatus of claim 11 wherein said means storing the digital manifestations of the work functions and their respective corresponding durations comprises a recirculating digital memory having a cycle time which is substantially shorter than an increment of time counted by said time counter.
